ATTORNEY

UNITED STATES PATENT OFFICE.

WILLARD C. BEACH, OF NEWARK, NEW JERSEY.

AIR BRUSH.

Application filed April 28, 1923. Serial No. 635,286.

To all whom it may concern:

Be it known that I, WILLARD C. BEACH, a citizen of the United States of America, residing at Newark, in the county of Essex and State of New Jersey, have invented new and useful Improvements in Air Brushes, of which the following is a specification.

This invention relates to improvements in air brushes as used in applying paint and the like in the form of a spray and has as one object to provide a device having a single control means for air and liquid, the same being arranged in convenient position for operation.

Another purpose is to produce an air brush exceptionally easy to handle and having unusually few parts, simple in construction and not readily liable to fail in operation.

A further aim is in the provision of means for adjusting the air in accordance with requirements during operation of the brush and also means for avoiding back pressure or clogging the operative parts by the liquid.

These and analogous aims, objects and purposes, which will become apparent as the description progresses, are accomplished by the novel construction, arrangement and combination of parts hereafter described and shown in the annexed drawings, forming an essential part of this disclosure, and in which:—

Figure 1 is a side view, mainly in section of assembled parts constituting the invention.

Figure 2 is a top plan view of the same, parts being broken away to show the arrangement of parts.

Figure 3 is a front elevational view of the same.

Figure 4 is an enlarged transverse sectional view taken on line 4—4 of Figure 1.

Figure 5 is a partial rear view of the device.

Figure 6 is an enlarged transverse sectional view through the handle, taken on line 6—6 of Figure 1.

Figure 7 is a side view of the liquid inlet

control valve plug and its adjusting means.

Figure 8 is a side view of the air control valve plunger in detail.

Figure 9 is a similar view of the air control valve plug.

Figure 10 is a perspective view showing the trigger and associated parts.

As shown in the drawings, the apparatus somewhat resembles in general appearance a pocket or holster carried gun and consists of a body or barrel 15 formed integrally with a handle or hilt 16 extending nearly at a right angle from a point to one side of the center of length of the body.

Said handle is hollow in construction, consisting of walls 17 and 18 integrally joined at one side and open at the other, the marginal edges of which present stepped or shouldered surfaces 19 to receive an inset cover plate 20, forming with the mentioned elements a smooth and comfortable feeling handle.

Extending inward from this element 18 is a relatively narrow solid central rib portion 21 having two projecting spaced lugs 22, into which are threaded the screws 23, counter-bored into the plate 20 and holding it rigidly in position.

Projecting integrally downward from the rib 21, beyond the handle, is a nozzle 24, screw-threaded exteriorly to receive a coupling (not shown) used to connect an air hose, and also having an internal thread 25 in which is fitted a tubular adjusting screw 26.

The rib contains a bore 27 in register with the opening nozzle 24 and in which is a helical compression spring 28, abutting respectively the adjusting screw 26 and the base 29 of a valve plug.

This plug has an extension 30 entering the spring and a conical contact element 31 suited to engage the valve seat 32 formed at the inner end of the bore 27.

A reduced neck 33, above the conical portion of the valve plug, leads to a triangular stem 34, the rounded longitudinal edges of which are fitted to slide freely in a bore 35 formed in axial register with the bore 27 but of lesser diameter.

In the upper end of the bore 35 is a slideable plunger 36 having a reduced lower end 37 normally in contact with the stem 34 of the conical air valve.

5 Extending from the front of the handle is a rigid guard 38, relatively narrow and adapted to project between the fingers of an operator so that two of the fingers may make contact with the wall 18 when grasping the 10 implement and the remaining fingers actuate the trigger 40 as further described, and in order to further lighten the weight of the structure a chamber 39 is interposed between the rib 21 and wall 18, in the lower half of the handle.

Said trigger 40 is generally outwardly curved and formed with an arm 41 on its rear surface, the same extending into a recess 42 in the upper end of the handle and is 20 bifurcated to receive one end of a link 44, held by the pin 45, the link extending into the handle, towards the back 17, and is connected by a pin 46 between the forks 47 of an angularly bent lever 48 pivoted at 49 to 25 extend through an opening 50 into the barrel 15 terminating in a fork 51.

Intersecting the opening at the end of the valve seat 32 is a transversely drilled passage 52, sealed by a plug 53, set flush in the wall 30 18, and intersecting the passage 54, parallel with the wall 18 and directed angularly outward through a lateral extension 55 of the barrel 15, its outer end being sealed by a plug 56.

35 Said extension is disposed lengthwise along one side of the barrel and contains a passage 57, intersecting the passage 54, and sealed at its front end by a plug 58, an angularly drilled opening 59 connecting the passage 57 with the counterbored air equalizing chamber 60 in the front end of the barrel.

In this chamber is secured the spray head 61, the same being substantially cylindrical, having a central annular recess 62, and 40 formed at its rear with a threaded shank 63 fitting the screw threads 64 of the body or barrel 15.

The outer portion of the spray head is formed into a cone 65 having a reduced cylindrical end 66 containing a relatively small axial opening 67 leading to the main central bore or fluid equalizing chamber 68, there being a conical valve seat 69 at its junction with the opening 67.

55 Threaded on the outer end of the barrel 15 is a cap 70, knurled to permit movement by the hand and having a conical part 71 bored to present a definite annular space 72 between it and the cone 65, and in register 60 with the opening 67 is a hole 73 formed through the end of the cap.

It is to be noted that the internal threads 64 are extended nearly to the junction of the handle 16 and at the end of the threads is a 65 hollow screw 74, through the bore of which

passes a plunger rod 75 having a conical valve plug 76 at its end controlling the passage through the valve seat 69.

A similar hollow screw 77, spaced forward of the crew 74, also acts as a guide and between these screws is disposed a fibrous packing 78 in contact with the rod.

Formed with the sleeve 86 is an enlarged head 87 having a longitudinally corrugated exterior and containing a recess 88 in which is received the head 89 of the stop 83, the stop passing freely through the wall at the bottom of the recess.

A raised lug 90 on the upper surface of the barrel has fastened upon it a flat spring 80 91 by screws 92, the outer, free end of the spring being shaped to present a detent 93, engageable in the corrugations of the head 87, thus holding the sleeve 86 in any adjusted position but permitting it to be turned by the application of force, the end 94 of the spring being up-turned for convenience in raising the detent.

By screwing the sleeve 86 inwardly it will be apparent that the distance which the 90 valve and its rod can be moved may be limited or all motion prevented, as may be desirable in transporting the device.

In operation, a flexible tube or hose leading from the source of liquid supply is connected to the nozzle 79 and a similar hose, communicating with a supply of compressed air, is connected to the nozzle 24.

The implement is grasped by the hand in such manner that two of the fingers rest upon the trigger 40 and the other two below the stop 38 on the surface 18, in which condition the appliance is ready to operate.

Upon applying pressure to the trigger, the link 44 will be depressed, forcing the 105 valve 32 from its seat in opposition to the closing spring 28, the entering air from the hose passing through the hollow screw 26, opening 27, past the valve 32, into the bore 52, thence the bore 54, through the passages 110 57 and 59 into the chamber 60, past the flattened parts 61' of the spray head 60 into the space 72 and eventually out of the opening 73.

As the link 44 in its movement actuates 115 the lever 48, its fork 51 presses the nut 84 outwardly, compressing the spring 85 and through its connections retract the valve plug from its seat 69, allowing the liquid entering through the nozzle 79 to pass out of the bore 67 and commingle with the air from the annular space 72, dispensing the same in a fine spray as required.

Immediately upon relaxing the trigger the springs 28 and 83 return the valves to 125 their initial closed positions and it will be apparent that, due to the packing 78, none of the liquid can pass rearward into the apparatus to clog or interfere with its working.

Although I have described my improvements with considerable detail and with respect to certain particular forms of my invention, I do not desire to be limited to such details, since many changes and modifications may well be made without departing from the spirit and scope of my invention in its broadest aspect.

Having thus described my invention, what I claim as new and desire to secure by Letters Patent, is:—

1. An air brush comprising a barrel having an axial bore and an air duct parallel thereto, a conical spray head fixed in said bore, a cap removably engaged over said head, there being an annular space therebetween communicating with the air duct, a liquid inlet to the bore adjacent the bottom of said head, a valve controlling the passage in said head suited to engage a hose, a single, horizontally disposed plunger rod combined with said valve, guides adjustably spaced in the bore of said barrel, a packing for said rod disposed between said guides all of said elements being inclosed in the barrel, means for directing compressed air into the duct, and a single means for simultaneously controlling the entrance of air and operation of said valve.
2. An air brush comprising a tubular barrel having an axial bore and an air duct parallel thereto, a conical spray head fixed in said bore, a cap removably engaged over said head, there being an annular space therebetween communicating with the air duct, a liquid inlet to the bore adjacent said head, a valve controlling the passage in said head suited to engage a hose, a single, horizontally disposed plunger rod combined with said valve, adjustable guides through which said rod operates, a head adjustably engaged on said rod, a sleeve adjustable in said barrel containing said head, said sleeve limiting the action of the valve plunger rod, a spring in said sleeve urging the valve into closing position, said spring and sleeve being enclosed, and means for retracting the valve, said retracting means also operating to admit air to the duct.
3. An air brush comprising a tubular body having an integral angularly extending handle, the bore of said body being internally screw-threaded at each end, the outer end being counterbored beyond the threads, an annularly recessed spray head held in the counterbore, means for conducting air to the recess of said head, a cap engaging said body spaced exteriorly said head, an inlet nozzle communicating with the core, a valve controlling the passage through said head, said valve having an elongated stem constituting a single, horizontally disposed operating plunger, guides for said stem engaging the internal thread of said body, a packing surrounding said

stem compressed by said guides, a collar adjustable on said stem, a spring pressing said collar to close said valve all within said barrel, a lever pivoted in said handle opposed to said spring, and a trigger for actuating said lever, said trigger controlling the air inlet to said head.

4. An air brush comprising a tubular body having an integral angularly extending handle, the bore of said body being internally screw-threaded at each end, the outer end being counterbored beyond the threads, an annularly recessed spray head held in the counterbore, means for conducting air to the recess of said head, a cap engaging said body spaced exteriorly said head, an inlet nozzle communicating with the bore, a valve controlling the passage through said head, said valve having an elongated stem constituting a single, horizontally disposed operating plunger, guides for said stem, a sleeve engaging the threads at the opposite end of said body, said sleeve having an enlarged corrugated head, a headed element in said sleeve, said element adjustably engaging said stem, a lock nut on said stem abutting said element, a compression spring in said sleeve abutting the lock nut, means for holding said sleeve in adjustment, and means for compressing said spring and retracting said rod.

5. An air brush comprising a tubular body having an integral angularly extending handle, a paint inlet suited to receive a hose; a spray head, a valve controlling the passage in said head, means for adjusting the operative length of said valve, means for adjusting the movement that can be imparted to said valve, a spring detent engaging the last named adjusting means, a forked lever engaging said valve, a link extending outward from said handle, a forked lever connected to said link, a trigger pivotally engaging said link, and a single, horizontally disposed means operated by said link and forked lever for admitting air and paint to said spray head.

6. An air brush comprising a barrel having an axial bore and an air duct parallel thereto, a conical spray head fixed in said bore, a cap removably engaged over said head, there being an annular space therebetween communicating with the air duct, a paint inlet to the bore adjacent said head, a valve controlling the passage in said head suited to engage a hose, a suitable, horizontally disposed means for adjusting the movement of said valve, a handle integral with said barrel, an air inlet combined therewith, a forked lever pivoted in said handle engaging said valve, a trigger pivoted on said handle, a link connecting said lever and trigger, a spring actuated valve in said handle controlling passages between said air inlet and the air duct, and means operative be-

tween said air valve and said link for opposing the spring to admit air upon actuation of said trigger.

7. An air brush comprising a tubular body having an integral angularly extending handle, inlet nozzles for paint and air combined respectively with the body and handle, a spray head having a mixing chamber for the paint and air, a valve controlling the discharge passage of the paint, a valve regulating the inlet of air, a single, horizontally disposed plunger for controlling both valves, independent springs arranged axially of each valve, adjustable means controlling the opening of the paint valve, a trigger pivoted in said handle near its junction with the barrel, and means actuated by said trigger and engaging said plunger for opening both of said valves simultaneously.
8. An air brush comprising a tubular body having an integral angularly extending handle, a spray head having a mixing chamber for the paint and air, and further provided with a main central bore or fluid

equalizing chamber, and an air equalizing chamber surrounding said spray head, an air passage located in the said integral angularly extending handle and communicating with the said air equalizing chamber, a liquid supply passage communicating with the said tubular body in close proximity to the main central bore or fluid equalizing chamber of the spray head, a packing located in said tubular body between the said liquid supply passage and the integral angularly extending handle of said body inlets for supplying paint and air to said spray head, and a single, horizontally disposed plunger in said central bore for controlling said air and paint inlets upon the operation of said brush.

This specification signed and witnessed this 19th day of February, 1923.
